BENJAMIN BELL, OF PHILADELPHIA, PENNSYLVANIA.

PNEUMATIC SPRING.

971,583.

Specification of Letters Patent.

Patented Oct. 4, 1910.

Application filed August 12, 1909. Serial No. 512,569.

To all whom it may concern:

Be it known that I, BENJAMIN BELL, a subject of the King of Great Britain, residing at Philadelphia, in the county of 5 Philadelphia and State of Pennsylvania, have invented certain new and useful Improvements in Pneumatic Springs, of which the following is a specification.

The object of this invention is to provide 10 a novel, simple and efficient pneumatic spring which may be adapted for use in connection with vehicles and in various other connections.

The invention consists in the novel construction and combinations of parts which 15 will be hereinafter fully described and particularly claimed.

In the drawings:—Figure 1 is a vertical section of one form of embodiment of my 20 invention. Fig. 2 is a horizontal section thereof on line 2—2 of Fig. 1. Fig. 3 is a development of a portion of the tubular diaphragm, partly broken away and shown in section. Fig. 4 is an edge view of the portion 25 of the diaphragm shown in Fig. 3. Fig. 5 is a vertical section of another form of embodiment of my invention. Fig. 6 is a vertical section of another form of embodiment of my invention.

Referring to Figs. 1, 2, 3 and 4: 3 and 4 30 designate upper and lower members respectively, and 5 a flexible diaphragm interposed between the members 3 and 4. The upper member 3 comprises a tubular portion 6, the upper end of which is closed by a head 7 which may be formed on or secured to the tubular portion 6. The bottom of the tubular portion 6 is provided with an outwardly-extending flange 8, and secured to the flange 40 8 by means of bolts 9 is a flange 10 which extends outwardly from a tubular portion 11 which forms in effect a part of the upper member 3 and a continuation of the tubular portion 6 thereof. The lower portion 11 45 of the member 3 is flared outwardly, as at 12, as shown, for a purpose hereinafter described. The lower member 4 comprises a tubular portion 13 the lower end of which is closed by a head 14 which may be formed on or secured to the tubular portion 13. The upper end of the lower member 4 is 50 provided with an inwardly-extending flange 15 and secured to the flange 15 by means of bolts 16 is a ring 17.

Extending downwardly from the end head 7 of the upper member 3, is a centrally-

arranged tube 18 which may be formed on or secured to the end head 7; and extending upwardly from the end head 14 of the lower member 4 and into the tube 18, is a centrally-arranged rod 19 which may be formed on or secured to the end head 14. The upper end of the rod 19 terminates below the top of the tube 18, and it will thus be seen that the tube 18 and rod 19 form a suitable 60 guiding device for the upper and lower members 3 and 4, whereby said members may be moved toward and from each other and held in proper relation with respect to each other.

The end head 7 of the upper member 3 is provided with an exteriorly-arranged ring 20, and the end head 14 of the lower member 4 is provided with an exteriorly-arranged ring 21, which rings 20 and 21 form a means 75 whereby the members 3 and 4 respectively may be attached to any suitable devices in connection with which it is desired to use the spring. The upper ring 20 is formed on a rod or stem 22 which is screw-threaded 80 and screwed into the end head 7 of the upper member 3; and the lower ring 21 is formed on the lower end of the rod 19 hereinbefore mentioned, which rod extends through the end head 14 of the lower member 4. The rod 19 is screw-threaded and screwed into the end head 14, and a suitable jam nut 23 is provided between which and the end head 14 packing 24 is arranged.

The lower member 4 extends into the upper member 3, as shown, and the interior diameter of the upper and outer member 3 is greater than the exterior diameter of the lower and inner member 4, thus providing 90 a space between the two members 3 and 4 95 in which the diaphragm 5 is arranged.

The diaphragm 5 is made tubular in form and one end thereof is extended between the flanges 8 and 10 entirely around the upper member 3, and is firmly secured thereto by the bolts 9 in a manner to form an air-tight joint; and the other end of the tubular diaphragm 5 is extended between the flange 15 and ring 17, entirely around the member 4, and is firmly secured thereto by the bolts 16 in a manner to form an air-tight joint. The end portion of the tubular diaphragm 5 secured to the inner or lower member 4 is brought upwardly within the end portion of the diaphragm secured to the outer or upper member 3, bending the diaphragm so that it will appear substan-

tially U-shaped in cross section, as shown in Fig. 1, extending across the space between the members 3 and 4 and being in engagement with the inner wall of the upper member 3 below the flange 10 and with the outer wall of the lower member 4 below the flange 15.

10 The upper and lower members 3 and 4 respectively and the diaphragm 5 form walls of an inclosed air-chamber 25 into which air under pressure may be introduced through an opening 26 in the upper member 3, which opening 26 is closed by a suitable screw-threaded removable cap 27.

15 From the foregoing description it will be seen that after the compressed air has been introduced to the chamber 25 the members 3 and 4 may be moved toward each other against the spring or cushioning action of the air contained within the chamber. It will also be seen that, as the members 3 and 4 are moved away from each other by the air pressure within the chamber the ring formed by that portion of the diaphragm 5 extending across the space between the two members will increase in diameter, due to the outward flaring portion 12 of the outer member 3, thereby increasing the area of air pressure acting against the members 3 and 4 transversely of their direction of movement to move said members apart and compensating by such increased area for the decrease in air pressure per square inch due to the movement of the members away from each other, so that any desired resultant pressure may be maintained against the two members 3 and 4 in the direction of their movement away from each other, irrespective of the relative positions of said members.

20 The angle of the flaring portion 12 may be changed so that the area of pressure acting against the members 3 and 4 will increase with the movement of the members 3 and 4 away from each other, and decrease with the movement of the members 3 and 4 toward each other, in any desired manner, either to maintain a substantially constant resultant pressure against the members 3 and 4 in a direction away from each other irrespective of their relative positions, or so that the resultant pressure against said members may vary when they come to different relative positions, to suit any desired requirement of work of the pneumatic spring. This flaring portion 12 of the outer member 3 forms an important part of my invention, for by its use and variation any desired load may be carried by the upper member, supported by the lower member, and said load may be moved downwardly against the cushioning or spring action of the air pressure within the chamber 25 and returned to normal position by the pressure within the chamber 25, the angle of the flaring por-

tion 12 determining the resultant pressure against the members 3 and 4 to return the load to normal position by compensating by increased air pressure area for the decreased air pressure per square inch as the members 3 and 4 are moved in a direction away from each other.

25 The tubular diaphragm 5 is preferably made of rubber, and it is expansible in the direction of its width, so that when one end portion of the diaphragm is in engagement with the exterior wall of the inner member 4 the other end portion of the diaphragm may expand into engagement with the interior wall of the outer member 3; and means are provided to prevent the diaphragm from expanding in the direction of its length under the air pressure within the chamber 25, to prevent the diaphragm from being blown out through the space between the members 3 and 4. As a suitable means to prevent the tubular diaphragm from expanding in the direction of its length as just mentioned, I provide a series of parallel threads 28 which extend longitudinally of or in the direction of the length of the tubular diaphragm, and which are embedded in the rubber of the diaphragm as shown in Figs. 3 and 4.

30 The construction shown in Fig. 5 is identical with the construction shown in Figs. 1 and 2, excepting that the wall of the lower portion 11^a of the upper member 3 is made parallel with the tubular portion 13^a of the lower member 4. It will thus be seen that in the construction shown in Fig. 5 the area of pressure against the members 3 and 4 transversely of their directions of movement will remain constant irrespective of the relative positions of said members, thus eliminating the compensating feature present in the construction shown in Fig. 1 due to the outwardly flaring portion 12 shown in Fig. 1 and previously described herein.

35 The construction shown in Fig. 6 is designed to act as a vacuum chamber, and to act the reverse of the construction shown in Fig. 1; that is to say, the construction shown in Fig. 1 is adapted to support a load by moving the members 3 and 4 toward each other, and the construction shown in Fig. 6 is adapted to support a load in suspension by moving the members 3 and 4 in directions away from each other. The construction shown in Fig. 6 includes the upper member 3 and the lower member 4, and is identical with the construction shown in Fig. 1, with the following exceptions:—The bottom portion of the tubular portion 6^a is flared outwardly, as at 30, and the bottom of the outwardly flaring portion 30 is provided with an outwardly-extending flange 31. Secured to the flange 31 by means of bolts 32 is a ring 33. The upper end of the lower member 4 is provided with an inwardly extending flange 34, and secured to

the flange 34 by means of bolts 35 is a flange 36 which extends inwardly from a tubular portion 37 which forms in effect a part of the lower member 4 and a continuation of the tubular portion 13 thereof. Arranged within the space between the members 3 and 4 is a tubular diaphragm 38, one end of which is extended between the flanges 34 and 36 entirely around the lower member 4 and is firmly secured therebetween by the bolts 35 in a manner to form an air-tight joint. The other end of the diaphragm 38 is extended between the flange 31 and ring 33 entirely around the member 3 and is firmly secured therebetween by the bolts 32 in a manner to form an air-tight joint. The diaphragm 38 extends across the space between the members 3 and 4 similar to the manner in which the diaphragm 5 extends across the space between the members 3 and 4 as shown in Fig. 1, excepting that the diaphragm 38 is made the reverse of the diaphragm 5 shown in Fig. 1, the parts of the members 3 and 4 being exposed to the external air, while the similar parts of the diaphragm 5 shown in Fig. 1 are exposed to the interior of the chamber 25.

From the construction shown in Fig. 6 as just described, it will be seen that after air has been exhausted from the chamber 25^a formed by the members 3 and 4 and diaphragm 38 to form a partial vacuum within the chamber, the members 3 and 4 may be moved away from each other against the spring or cushioning action of the partial vacuum within the chamber 25^a. It will also be seen that as the members 3 and 4 are moved toward each other by the partial vacuum within the chamber 25^a, the ring formed by that portion of the diaphragm 38 extending across the space between the two members will decrease in diameter due to the outward flaring portion 30 of the upper member 3, thereby decreasing the area of the partial vacuum acting upon the members 3 and 4 within the chamber 25^a transversely of the directions of movement of the members 3 and 4, and compensating by such decreased area for the decrease of the partial vacuum within the chamber 25^a due to the movement of the members toward each other.

The angle of the flaring portion 30 may be changed to meet any desired requirements. Saving and excepting that in the construction shown in Fig. 6 a vacuum chamber 25^a is employed and that in the construction shown in Fig. 1 a compressed air chamber 25 is employed, and that the cushioning actions of the members 3 and 4 of the construction shown in Fig. 6 is directly opposite to the cushioning actions of the members 3 and 4 of the construction shown in Fig. 1, the results of the two con-

structions shown in Figs. 1 and 6 are substantially identical.

I claim—

1. In a pneumatic spring, two relatively movable members forming walls of an inclosed chamber and including adjacent walls which converge with respect to each other toward the interior of the chamber; and a flexible diaphragm secured to and interposed between said members and engaged with and extending across the space between said adjacent walls. 70 75

2. In a pneumatic spring, two relatively movable members forming walls of an inclosed chamber and including adjacent walls which converge with respect to each other toward the interior of the chamber; and a flexible diaphragm secured to and interposed between said members and having a portion extending across the space between 80 85 said adjacent walls and portions converging toward each other from the first named portion and engaged with said adjacent walls.

3. In a pneumatic spring, two relatively movable tubular members arranged one within the other and forming walls of an inclosed chamber, the outer wall of the inner member and the inner wall of the outer member converging with respect to each other toward the interior of the chamber; and a flexible diaphragm secured to and interposed between said members and engaged with and extending across the space between said inner wall and said outer wall. 90 95

4. In a pneumatic spring, two relatively movable tubular members arranged one within the other and forming walls of an inclosed chamber, the outer wall of the inner member and the inner wall of the outer member converging with respect to each other toward the interior of the chamber; and a flexible diaphragm secured to and interposed between said members and having a portion extending across the space between 100 105 said inner wall and said outer wall and portions converging toward each other from the first named portion and engaged with said inner wall and said outer wall. 110

5. In a pneumatic spring, two relatively movable members forming walls of an inclosed chamber and including adjacent walls which converge with respect to each other toward the interior of the chamber; a flexible diaphragm secured to and interposed between said members and engaged with and extending across the space between said adjacent walls; and means for guiding said members including a tube fixed to one of said members and a rod fixed to the other of said members and extending into said tube. 115 120

6. In a pneumatic spring, two relatively movable tubular members arranged one within the other and forming walls of an inclosed chamber, the outer wall of the inner member and the inner wall of the outer 125 130

member converging with respect to each other toward the interior of the chamber; a flexible diaphragm secured to and interposed between said members and engaged 5 with and extending across the space between said inner wall and said outer wall; a centrally-arranged tube fixed to one of said members; and a centrally-arranged rod fixed to the other of said members and extending 10 to the other of said members and extending into said tube.

7. In a pneumatic spring, two relatively movable members arranged one within the other and out of contact with each other and forming walls of an inclosed chamber; a

flexible diaphragm secured to and interposed 15 between said members; a centrally-arranged tube fixed to one of said members; and a centrally-arranged rod fixed to the other of said members and extending into said tube, said tube being movable within one of said 20 members and said rod being movable within the other of said members.

In testimony whereof I affix my signature in presence of two witnesses.

BENJAMIN BELL.
